UNITED STATES PATENT OFFICE.

DAVID E. BLAIR, OF MONTREAL, QUEBEC, CANADA.

DUMP-CAR.

1,075,687.

Specification of Letters Patent. Patented Oct. 14, 1913.

Application filed September 8, 1909. Serial No. 516,875.

To all whom it may concern:

Be it known that I, DAVID E. BLAIR, of the city of Montreal, in the Province of Quebec and Dominion of Canada, have invented certain new and useful Improvements in Dump-Cars, of which the following is a full, clear, and exact description.

This invention relates to dump-cars of the type having side doors which are automatically released and opened when the car is tilted to one side so as to open up the whole side of the car for the discharge of the load.

The car body is mounted upon the center sills of the underframe and is supported centrally thereon so that the entire load is carried by the floor of the car. This makes it necessary that the car body be made very strong not only to sustain the load but to resist the strains to which the car is subjected.

The main object of the invention is to provide a car body of improved construction that will be sufficiently strong to carry the load and resist the various strains to which it is subjected; that can be quickly and easily turned to one side to discharge the load through side doors that will operate automatically upon the release of the car body; and that can be returned to its normal position with great facility. For particulars of operating mechanism, reference may be had to my complementary application, Ser. No. 516,874.

In the drawings which illustrate my invention: Figure 1 is a plan view of a car constructed according to my invention. Fig. 2 is a side elevation of the car shown in Fig. 1, the left half being in central longitudinal section. Fig. 3 is an end elevation of the car. Fig. 4 is a transverse sectional view on the line 6—7 of Fig. 2, the broken lines showing the car in tilted position. Fig. 5 is a perspective view of one of the compartments of the car showing the side doors and the locking mechanism therefor.

The body of the car constructed according to my invention, is divided into a series of compartments by means of transverse partitions or diaphragms.

Referring to the drawings, 8 designates the compartments, and 9 the diaphragms or partitions separating same. In the view shown in Fig. 5, the end compartment is bounded upon one side by the vertical end wall 12 of the car, and upon the opposite side by the partition or diaphragm 9.

11 designates the vertical side plates of each compartment, said side plates constituting the fixed side wall of the car-body. The side plates 11 are connected to the diaphragms 9 by the angle-plates 13, while the floor 10 is fixed to the side-plates by means of the angle-bars 14.

15 designates the angle-plates connecting the floor member 10 with the diaphragms 9, said diaphragms being provided at the top with angle-bars 16 to stiffen them. The angle-bars 15 and 16 with the connecting plates or diaphragms 9, form girders which support the car-body and prevent same from buckling or twisting. These girder members are very essential in the construction of a car of this type, said car being supported centrally and mounted to tilt pivotally upon segments underneath the car-body. The car-body is stiffened by angle-bars 17, which extend longitudinally underneath the same throughout its length. End stakes 18 support and strengthen the end members 12 of the car and are fastened to the angle-bars 17. 75 The sides of the compartments are stiffened and strengthened by the members 19. The three vertical sides of each compartment are thus fixed, the fourth side comprising the door 20 mounted upon hinges 21 beneath said door, said hinges extending upwardly on the outside of the doors to form braces 22 and each being provided at the top with a thickened lip 23, which is adapted to engage the lug or catch 24, fixed to the longitudinal shaft 25 mounted in bearings 26 placed at intervals throughout the length of the car. The shaft 25 is operated by means of a lever 27 fixed to the square end 28 of the shaft. 80 The lever 27 is pivoted at its opposite end to the link 29 provided with an adjusting device 30, said link being pivoted at its opposite end 31 to the underframe of the car. As the car-body is tilted, the link 29 and lever 27 operate to turn the shaft 25, raising the locks or catches 24 and releasing the doors 20, as more fully hereinafter explained. The doors 20 swing outwardly upon the hinges 21 and fall downwardly 85 upon the buffer beam 32, which extends along the side of the car, as indicated. The buffer beam 32 is fixed to a series of hangers 33 mounted upon hinges 34. The hangers 33 are pivotally connected with link members 35 which are pivoted at their opposite ends 36 to the underframe. When the car 90 is tilted to one side, and the doors swung

105 upon the buffer beam 32, which extends along the side of the car, as indicated. The buffer beam 32 is fixed to a series of hangers 33 mounted upon hinges 34. The hangers 33 are pivotally connected with link members 35 which are pivoted at their opposite ends 36 to the underframe. When the car 110 is tilted to one side, and the doors swung

outwardly and downwardly, they fall against the buffer beams 32, which are held at the proper angle by means of the links 35. The doors 20 thus assume the position shown in dotted lines in Fig. 4, and the load is discharged in such a manner that said doors prevent the contents from falling underneath the car and piling up on the rails and thus blocking the tracks. The load may be scraped away from the car doors, if necessary, by any suitable means.

The car body is mounted upon longitudinal center sills 37 which are supported by the frame bolsters 38, the center sills being connected at intervals by stiffening plates 39 and cover plates 40. The car body is mounted centrally upon castings 41, secured to the under side of the car body between the longitudinal angle bars 17, said castings 41 being in the form of a segment curve 42. This segment is provided with a series of teeth 43 which operate in the cover plates 40 to prevent slipping during the operation of tilting the car. The center of support of the car body is preferably out of line with the central axis of said car body, in order that the car will dump itself automatically. The car body is provided on its under side, opposite the doors, with a rack 44, pivoted at 45, said rack coöperating with a pinion 46, actuated by a shaft 47, adapted to revolve in bearing plates 48, suitably fixed to the under frame of the car.

49 designates longitudinal supporting members mounted upon the side sill 50, upon which the car is adapted to rest in its normal position.

The operation of unloading the car will

be readily understood from the foregoing description. When the car is loaded in its normal level position, it is held in place by the engagement of the pinion 46 with the rack 44, said pinion being locked and released by any well known mechanism for this purpose. When it is desired to discharge the contents of the car, the pinion 46 and shaft 47 are released, and as the center of support of the car body is slightly out of line with the central axis of the car body, and toward the fixed side of the car, 50 said car will automatically tilt in the direction shown in broken lines in Fig. 4, the pinion 46 working easily upon the rack 44. As the car tilts toward the side, the doors are automatically released from the locks 55 or catches 24 and fall outwardly and downwardly being supported by the buffers 32. The contents of the car discharge by gravity, and the doors 20 prevent the load from spreading underneath the trucks. 60

Having thus described my invention, what I claim is:—

A car body comprising a continuous fixed side, internal transverse girders supported at the approximate centers of their lower 65 edges, a floor, and means connecting said side and said floor to said transverse girders, whereby said floor and side are supported from said girders.

In witness whereof I have hereunto set 70 my hand in the presence of two witnesses.

DAVID E. BLAIR.
